UNITED STATES PATENT OFFICE.

JAMES E. BRADLEY, OF JACKSON, MICHIGAN, ASSIGNOR OF ONE-HALF TO
MARCUS W. ROBINSON, OF SAME PLACE.

TUCK-MARKING DEVICE FOR SEWING-MACHINES.

SPECIFICATION forming part of Letters Patent No. 451,450, dated May 5, 1891.

Application filed August 21, 1890. Serial No. 362,681. (No model.)

To all whom it may concern:

Be it known that I, JAMES E. BRADLEY, of Jackson, in the county of Jackson and State of Michigan, have invented a new and useful 5 Improvement in Tuck-Markers, of which the following is a specification.

My invention relates to tuck-markers for sewing-machines; and the object of my improvement is to provide an improved attachment for sewing-machines by which the goods may be marked as a guide for making the next fold. I secure this object in the device illustrated in the accompanying drawings, in which—

15 Figure 1 is a plan view, Fig. 2 a side elevation, and Fig. 3 an end elevation, of a device embodying my invention and the lower end of the needle-bar of a sewing-machine; and Fig. 4 is an elevation of the stop by 20 which the cloth is guided.

Similar letters refer to similar parts throughout the several views.

A is a lug by which the device is secured to the cloth-plate of the machine.

25 B is a bar rigidly secured to the lug A and extending therefrom in a direction at right angles to the motion of the cloth in the machine.

C is a metal block provided with an aperture through which the rod B extends and 30 adapted to slide along said rod.

D is a set-screw by which the block C may be secured in the desired position upon the rod B.

H is a lever pivoted at I to the block C and 35 adapted to oscillate in a vertical plane parallel to the rod B. The lever H is provided with an arm a extending to the left, and an arm b extending to the right, of the pivot I. The arm a is of about the length of the rod 40 B, and is bent at its end to form the vertically-extending portion H'. A notch h is formed in the lower end of the portion H' of the lever H.

S is a spring secured to an extension K from 45 the block C, and pressing upward because of its elasticity upon the free end of the arm b of the lever H, thus pressing the end of the arm a downward.

E is a rod extending from the block C parallel to the rod B, then turning and extend-

ing beneath the free end of the arm a of the lever H.

G is a plate secured to the end of the rod E, and provided with a spur G', adapted to extend into the notch h.

55 F is an elastic strip extending parallel to the rod B upon the side of said rod which is toward the operator.

M is the lower end of the needle-bar.

L is a ring, and c a set-screw by which the 60 needle is secured to the needle-bar. m is an arm extending from the ring L under the arm a of the lever H.

N is a stop by which the cloth is guided. 65 The rod B extends through an aperture in the stop N, and said stop is adapted to be moved along said rod.

n is a set-screw by which the stop N is secured in the desired place upon the rod B.

70 The operation of the above-described device is as follows: The device is secured to the cloth-plate of the machine by a screw passing through a hole in the lug A, the arm B extending in a direction at right angles to the motion of the cloth in the machine, its free 75 end coming just to the right of the needle-bar. The ring L is adjusted to the needle-bar and secured in place by the set-screw c, at the same time securing the needle in place, the arm m extending under the arm a of the lever H.

80 The block C is now moved along the rod B until the end H' of the lever H is at a distance to the left of the needle-bar corresponding to the width of tuck desired. The stop N is moved to the right a distance corresponding to the width of the tuck. The cloth is guided by its right-hand edge coming against the face of the stop N. The cloth passes under the strip F and over the rod E and spur G'. When the machine is being operated to sew one tuck, the arm a of the lever H is raised by the arm m with the ascending needle-bar and allowed to descend when the needle-bar descends, the spring S pressing the end H' of said lever down upon the cloth, 95 bending the cloth by means of the notch h over the spur G' to mark the next tuck.

90 In the above-described device the marking-arm descends with a comparatively moderate velocity, so that while the momentum of the 100

arm assists to form the crease, a yielding pressure of the marker upon the cloth is secured and a quick blow is avoided, so that the cloth is not liable to be perforated.

5 Very little power is required to operate the above-described device, as the power expended by the sewing-machine in raising the marking-arm is stored up in the actuating-spring, and is again restored to the sewing-machine 10 by the descending arm.

Having fully described my invention, what I claim, and desire to secure by Letters Patent, is—

15 The combination of the securing-lug A, a rod B, extending from said lug, the block C,

adjustable on said rod, a marking-lever pivoted to said block, a spring upon said block adapted to press the marking end of said lever downward, a bar extending from the needle-bar of the machine under the marking-arm of said lever, a notch h in the marking end of said lever, and a rod E, extending from said block under the marking end of said lever and provided with a spur G', adapted to extend into the notch h, substantially as shown 20 and described.

JAMES E. BRADLEY.
